FOOD WASTE DISPOSER

Richard G. Hawkins, Bell, Calif., assignor to W. T. Hedlund Company, Los Angeles, Calif., a corporation of California

Filed Nov. 20, 1961, Ser. No. 67,592

Term of patent 14 years

(Cl. D55—1)

FIG. 1 is a front elevational view of a food waste disposer showing my new design.

FIG. 2 is a side elevational view thereof.

FIG. 3 is a rear elevational view.

FIG. 4 is a top plan view.

The dominant features of the design are shown in the drawing in full lines.

I claim:

The ornamental design for a food waste disposer, substantially as shown and described.
